UNITED STATES PATENT OFFICE.

BERTHA KOLLIN, OF NEW YORK, N. Y.

DOLL.

Application filed February 6, 1924. Serial No. 690,936.

The present invention relates to dolls and the primary object thereof is to provide a double figured doll whereby both sides of the doll may be utilized as the front for representing different characters, or like characters in a different attire and facial expression.

Another object of the invention is to provide a double figured doll having its faces arranged in such a manner with respect to the legs which are capable of swinging movement back and forth from a soft body, that when one side of the doll is arranged to simulate a person in a sitting posture, the opposite side will appear as if kneeling.

Other objects and advantages of the invention will appear in the following detailed description, taken in connection with the accompanying drawings, wherein similar reference characters designate corresponding parts throughout the views, and in which drawings:

Figure 1 is a front elevation of one of the characters as disclosed at one side of the doll, the doll being shown in a kneeling position.

Figure 2 is a perspective view of the doll as shown in Figure 1 and showing a portion of the attire disposed at the opposite side of the doll.

Figure 3 is a front elevation of the character as disclosed at the opposite side of the doll, the doll being shown in a sitting posture.

Figure 4 is a vertical section showing the manner in which the legs are formed to permit of a swinging movement.

Figure 5 is a fragmentary elevation showing the manner of construction at the joint between one of the legs and body portion.

Figure 6 is a fragmentary elevation showing the manner of construction at the joint between one of the arms and body portion.

Figure 7 is a fragmentary top plan showing the joint between one arm and body portion.

In the example as shown, the doll may represent Cinderella, sadly dressed in rags on one side and happily dressed in silk on the other side, with facial expressions accordingly. This has been shown by way of example; but it is to be understood that the clothes and hair may be changed in accord-

ance with the character to be illustrated.

Referring to the drawings in detail, A designates a double figured doll and B a garment therefor, said garment formed with a well made portion C and a poor and ragged portion D.

The doll A consists of two pieces of materials 10 and 11 such as cloth or the like cut to the desired shape and sewed together along their marginal edges. A small portion of the pieces 10 and 11 may be left unsewed in order to permit the reversing thereof and to enable the placing of a filler 12, such as cotton batting, in the doll for the shaping thereof. Each of the pieces 10 and 11 have faces stamped or otherwise delineated on the head portions thereof so that when the doll is filled, the head 13 will be formed with two diametrically disposed faces.

The legs 14 of the torso or body 15 have the feet 16 thereof disposed in oppositely extending relation to one another with the heel portions adjacent one another as clearly shown in Figures 2 and 3. A stitching 17 extending at a right angle to the major axis 80 of the legs 14 and at a point adjacent the crotch 18, forms a hinge which permits of the legs to be swung in either direction as shown in dotted lines in Figure 4. It can therefore be seen that by so disposing the feet in oppositely extending relation to one another, the legs 14 will lie flat when swung in either direction.

The arms 19 are stitched as at 20 for providing a hinge in order that the arms may also be swung in either direction as is shown by the dotted lines in Figure 7. This stitching 20 extends at an angle to the major axes of the arms 19 for permitting the arms to be placed behind the doll or in its lap.

These stitches 17 and 20 pass through the filler 12 and stitch together the pieces 10 and 11 as clearly shown in Figure 4.

The hair or wig 21 which is parted in the center and falls over each shoulder of the doll, may be made with one portion curled as at 22 and the other portion straight as at 23. These portions 22 and 23 may divide just above the shoulder; the curled portion falling over the garment portion C and the straight portion falling over the garment portion D. It can be seen

that by so parting the hair as at 24, a free space will be left for each face of the doll as there is no back to the wig.

It will be observed that by so arranging the faces with respect to the legs, which are capable of swinging movement back and forth from a soft body, that the doll when arranged to simulate a person sitting in one position, the opposite side will appear as if 10 kneeling.

While one character has been shown by way of example, it is to be understood that the faces and wearing apparel may vary in accordance with the character to be illustrated.

Changes in detail may be made without departing from the spirit or scope of my invention; but,

I claim:

20 1. In a doll having its head provided with two diametrically disposed faces, a pair of legs hingedly connected to the body of the doll and capable of being swung to extend in substantially right angular relation to either face of the torso of the doll, said legs having the feet thereof permanently disposed in oppositely, outwardly extending relation to one another.

25 2. A doll comprising a body, a head, diametrically disposed faces provided on the head of the body, a two part wig for the head comprising two differently formed portions, said wig being parted centrally of the head with unlike portions overhanging opposite sides of the body of the doll, arms hingedly connected to the body, and legs hingedly connected to the body having the feet thereof disposed in oppositely and outwardly extending relation to one another

and with the heel portions adjacent one another, said faces arranged in such relation with respect to the legs so that when the doll is arranged to simulate a person in a sitting posture at one side, the opposite side will appear as if kneeling.

3. As an article of manufacture a wig for a two faced doll, comprising two unlike portions simulating hair, parted at the sides and trailing off at each front of the doll, with the trailing sections of each portion concealed from one front of the doll by the opposite trailing sections and by the shoulders of the doll.

4. As an article of manufacture a wig for a two faced doll, comprising two portions simulating hair, parted at the fronts and trailing off at the sides for providing a free space for permanent exposure of each face of the doll, and parted at the sides and trailing off at each front of the doll, for exposure at the front of each shoulder of the doll.

5. A doll having its head provided with two diametrically opposite faces, a pair of legs hingedly connected to the body of the doll and capable of being swung to extend in substantially right angular relation to either face of the torso of the doll, said legs having the feet thereof permanently disposed in oppositely, outwardly extending relation to one another, and a pair of arms normally disposed with the hand simulations thereof in either of the lap portions of the doll and being so connected to the main body whereby they may be swung to either side of the main body.

BERTHA KOLIN.
